UNITED STATES PATENT OFFICE.

EVERETT R. BURTNETT, OF LOS ANGELES, CALIFORNIA, ASSIGNOR OF ONE-HALF TO
HOMER A. BRUNELL, OF LOS ANGELES, CALIFORNIA.

PISTON-SLEEVE VALVE FOR L-HEAD MOTORS.

Application filed August 5, 1920. Serial No. 401,583.

To all whom it may concern:

Be it known that I, EVERETT R. BURTNETT, a citizen of the United States, residing at Los Angeles, in the county of Los Angeles and State of California, have invented new and useful Improvements in Piston-Sleeve Valves for L-Head Motors, of which the following is a specification.

The object of the present invention is to 10 provide a valve mechanism comprising a piston and sleeve combination which is applicable to L head internal combustion engines.

More particularly it is the object of the invention to provide a construction of this 15 character so arranged as to form a structure which will not be of a weight greater than the conventional type of internal combustion engines. The improved construction is also one which compared to a conventional internal combustion engine is not of increased 20 size in height, width or length.

The construction is also one which may be manufactured at a minimum cost and one which provides a valve mechanism in which 25 the necessity for adjusting and grinding of the valves is eliminated. The valve mechanism will also be silent in operation and will function more effectively and smoother with continued use. The construction is 30 one which permits of efficient functioning thereof even when the engine becomes heated. In addition to the greatly simplified construction provided by the invention the facility and ease with which the various 35 parts may be removed and examined is also greatly increased.

The invention will be readily understood from the following description of the accompanying drawings, in which

40 Figure 1 is an end view of an internal combustion engine constructed in accordance with the invention.

Fig. 2 is a side elevation of the same.

Fig. 3 is a longitudinal section through 45 the cylinder of the engine.

Fig. 4 is a transverse section through the same.

In the drawings I have exemplified the invention as embodied in an internal combustion engine having but one cylinder. It 50 will be obvious, however, that the invention is readily applicable to an engine having any desired number of cylinders.

The working cylinder of the engine is 55 shown at 1 having a water jacket 2 sur-

rounding the same with the casing 3 forming said water jacket also forming a casing 4 for a water jacket 5 which forms a continuation of water jacket 2 at one side thereof and surrounds a valve cylinder 6 longitudinally arranged with relation to cylinder 1 and disposed at one side thereof.

A block head 8 extends over the top of both cylinders 1 and 6 and is suitably bolted thereto. This head is recessed at its under side as shown at 9 in order to form a passageway between cylinders 1 and 6, and a spark plug 10 is received through the head so as to project within passageway 9. The head is provided with a suitable water cell 11 communicating with water jackets 2 and 4 and having a usual water outlet 12 located at the top thereof.

The working piston received within cylinder 1 is shown at 13 connected to a usual connecting rod 14 which is pivoted in usual manner to the main crank shaft 15. A shaft 16 controlling the valve mechanism extends parallel to shaft 15 and is arranged to be driven at half engine speed by the train of gears 17, 18 and 19.

Intake and exhaust ports 20 and 21 extend through casing 4 in lateral alignment so as to communicate with cylinder 6 at the side thereof opposite working cylinder 1. 85 A sleeve valve 22 is arranged for reciprocation within cylinder 6 and is connected by connecting rod 23 to an eccentric 24 keyed upon shaft 16 so that when main crank shaft 15 is rotated the sleeve valve will be reciprocated at one-half engine speed.

Intake and exhaust ports 25 and 26 are provided in sleeve 22 in longitudinal alignment with ports 20-21 respectively. The ports 25-26 are offset laterally in sleeve 22, 95 the intake port being arranged below the exhaust port. A fixed member 27 is positioned within sleeve valve 22 as by means of an annular flange 28 at the top of said member extending over the upper edge of 100 casing 4 and suitably secured thereto as by means of screws 29. The wall of member 27 is eccentrically arranged so that the bore 30 of said member is eccentric with relation to sleeve 22, as clearly shown in Fig. 4. 105 A valve piston 31 is arranged for reciprocation within the bore 30 and for this purpose is secured to connecting rod 32 which is in turn connected to an eccentric 33 arranged upon shaft 16.

A laterally elongated port 35 is provided in the member 27 for lateral and longitudinal alinement with ports 20—21. A plurality of ribs 36 are arranged in port 35 at the edge thereof adjacent sleeve 22, and a similar plurality of ribs 37 are arranged in port 35 at the edge thereof adjacent the bore 30. Each of these series of ribs are in lateral spaced relation and project inwardly 10 within port 35 only a portion of the distance across said port, so that both the passages 38 provided between ribs 36 and arranged to communicate with ports 25—26 and the passages 39 arranged between ribs 27 15 and adapted to communicate with the bore 30, are in connection with the laterally extending central portion of the port 35.

The operation is as follows:

With the parts in the position as shown 20 in Fig. 3, the cycle of operation is at the beginning of the firing stroke. As piston 13 is forced downwardly for causing rotation of the main crank shaft the connecting rods 23 and 32 will be actuated. These connecting rods are so arranged with relation 25 to the shaft 16 that as piston 13 moves downwardly the exhaust port 26 of sleeve 22 will be brought into communication with port 21 and ports 28. When piston 13 reaches the 30 end of its expansion stroke the piston valve 31 will uncover ports 39 thereby forming a passageway from the working cylinder through passageway 9, port 35 and port 26 to the exhaust port 21. During subsequent 35 upward exhaust stroke of piston 13 the exhaust gases will be forced outwardly through this passageway. As piston 13 thus moves upwardly downward movement of piston valve 31 is continued and sleeve 22 40 moves upwardly. When piston 13 has finished its exhaust stroke the piston valve 31 is below port 35 and the exhaust port of sleeve 22 is above said port thereby cutting off the registration of the openings providing 45 the exhaust passage.

In the suction stroke of piston 13 the piston valve will move upwardly and sleeve 22 will also move upwardly so as to cause intake port 25 to register with intake port 20 50 and the ports 26. A passageway from intake ports 20 to the working cylinder of the engine is thus completed. When piston 13 has reached the end of the suction stroke 55 a sufficient distance to nearly completely shut off ports 39. A lag for the fuel intake is thus provided.

As the piston 13 moves upwardly on the compression stroke, piston valve 31 will continue its upward movement to completely 60 shut off ports 39 thereby forming a closed chamber for the compression of the gases. At the same time the sleeve 22 moves downwardly to bring exhaust port 26 to its original 65 position. The cycle of operation is thus

completed and the parts are ready for the next subsequent cycle of movement.

Various changes may be made without departing from the spirit of the invention as claimed.

70

What is claimed is:

1. An internal combustion engine including a working cylinder, a valve cylinder at one side thereof having an interior stationary sleeve, a head for said cylinders forming a connecting passageway, between the working cylinder and the interior of the stationary sleeve, said stationary sleeve having transversely alined inlet and discharge ports, and reciprocating valvular means 75 within said stationary sleeve and within said valve cylinder, each functioning in connection with both of said ports.

2. An internal combustion engine including a working cylinder, a valve cylinder, a 85 stationary sleeve within said valve cylinder having a relatively thick wall, a passageway connecting the interior of said stationary sleeve and said working cylinder, laterally alined inlet and exhaust ports in said valve cylinder, a port extending through the wall of said stationary sleeve in alinement with said inlet and exhaust ports, a sleeve valve surrounding said stationary sleeve within said valve cylinder and having laterally and longitudinally offset inlet and exhaust ports, and a piston valve within said stationary sleeve.

3. An internal combustion engine including a working cylinder, a valve cylinder, a 100 passageway connecting the same, said valve cylinder having laterally alined inlet and exhaust ports, a sleeve valve within said valve cylinder having longitudinally and laterally offset inlet and exhaust ports, a 105 stationary sleeve within said sleeve valve having a port in alinement with the inlet and exhaust ports of said valve cylinder, and a piston valve within said stationary member.

4. An internal combustion engine including a working cylinder, a valve cylinder, a passageway connecting the same, said valve cylinder having laterally alined inlet and exhaust ports, a sleeve valve within said valve cylinder having longitudinally and laterally offset inlet and exhaust valves, a stationary sleeve within said sleeve valve having a port in alinement with the inlet and exhaust ports of said valve cylinder, and a piston 115 valve within said stationary member, the port of said stationary sleeve having dividing ribs adjacent said sleeve valve and adjacent said piston valve arranged in spaced relation along said port and forming a passage the length of said port between the same.

In testimony whereof I have signed my name to this specification.

EVERETT R. BURTNELL.
